UNITED STATES PATENT OFFICE.

HARRY RANDOLPH VAN DEVENTER, OF SUMTER, SOUTH CAROLINA, ASSIGNOR TO SPLITDORF ELECTRICAL COMPANY, OF NEWARK, NEW JERSEY, A CORPORATION OF NEW JERSEY.

GENERATOR-LAMP.

1,244,262.

Specification of Letters Patent. Patented Oct. 23, 1917.

Application filed January 11, 1917. Serial No. 141,833.

To all whom it may concern:

Be it known that I, HARRY R. VAN DEVENTER, a citizen of the United States, residing at Sumter, South Carolina, in the county of Sumter and State of South Carolina, has invented certain new and useful Improvements in Generator-Lamps, of which the following is a specification, reference being had to the accompanying drawing.

10

My invention relates to generator lamps particularly designed for use on bicycles or the like.

The objects of the invention are to provide a simple and efficient generator lamp in which all of the moving and more or less delicate parts are effectively housed and protected; also to provide a supporting device capable of holding the rotatable shaft of the lamp either in operative or inoperative relation to the vehicle wheel or other rotating part of the vehicle on which the lamp is supported; also to provide a support which will permit the lamp to be adjusted so as to assure that the axis of rotation of the rotating armature and its shaft lie in a plane intersecting the center of the wheel of the bicycle.

In the drawings, which show by way of illustration, one embodiment of the invention:—

Figure 1 is a side view showing my improved igniting and lighting device and its relation to the bicycle;

35 Fig. 2 is a vertical sectional view through the same; and

Fig. 3 is a horizontal sectional view on the line 3—3 of Fig. 2.

Fig. 4 is an enlarged sectional view 40 through the yielding device which holds the generating device in off position.

Referring more in detail to drawings:—

My improved generating and lighting device consists of a rotating armature 1, which 45 is provided with the usual generating coil. The armature has projecting from each end thereof, shaft sections, which together form the armature shaft, indicated at 2 in the drawings.

50 The armature 1 is mounted to rotate within the U-shaped magnet indicated at 3 in the drawings. Surrounding the magnet and the armature is an inclosing casing which consists of a body portion 4 made

folded at 5. Attached to the upper part of the body portion is an end plate 6 which is provided with an integral cup-like collar 7^a inclosing a bearing 7 for the armature shaft 2 and a downwardly extending flange 8, 60 which overlaps the body portion of the casing.

At the lower end of the body portion 4 there is another end plate 9 which is formed with a flange 10, overlapping the body portion of the casing and this end plate is formed with a cup-like collar 11^a which incloses and carries a bearing 11 for the armature shaft 2. The bearings 7 and 11 may be of any suitable ball bearing type. The shaft 70 2 projects below the bearing 11 and a driving wheel 12 is secured thereto by a set screw 13. The driving wheel has a projecting part 14 which is adapted to engage the tire or rim of the bicycle wheel for rotating the armature shaft. This driving wheel 12 is also formed with a projecting sleeve 15 which overlaps and completely houses the lower bearing 11 and prevents dirt and dust from getting into the bearing.

80 On the upper end of the armature shaft 2 there is a sleeve 16 which is secured to the shaft by a set screw 17. This sleeve is threaded to form a socket for the lamp 18. The sleeve 16 projects into a reflector indicated at 19 in the drawings. This reflector is firmly clamped to the casing of the generator and is provided with a sleeve 19^a on its lower side fitting over the cup-like collar 7^a. The lamp is carried at the upper end 90 of the sleeve and is located within the reflector. The end plates 6 and 9 are held on the body portion of the casing by a rod 20 which extends through the end plates and is provided with a nut 21 at one end thereof. Extending through the end plates 6 and 9 is a supporting stud 21^a which carries a lug 22 at its lower end and a nut 23 at its upper end. The casing is freely mounted on its stud 21^a and is normally 100 pressed toward the plane of the wheel of the bicycle, by a spring 24. When the casing is swung away from the plane of the wheel so as to move the driving wheel 14 of the armature out of engagement with the wheel 105 of the bicycle, it is held in this inoperative or off position by a yielding pin 25 carried by a tubular arm 26 attached to the stud 21^a and this yielding pin slips by the post 20. The pin 25 has a head 25^a at its inner end 110

engaging an internal shoulder 26' at the outer end of the tubular arm 26 and is pressed outwardly by a spring 26a. The lug 22 is pivotally connected to a link 27, by bolt 29 and in turn is pivotally connected by a bolt 30 to the supporting bracket 31 attached to one member of the fork of the bicycle by suitable clamping arms 32, 32, and bolts 33, 33.

10 From the above description it will be apparent that I have provided a generating and lighting device consisting of few parts which are simple in construction and which are free from all loose connections and movable contacts, inasmuch as the lamp is carried directly by the armature shaft and electrically connected to the coil on the armature shaft. The bearing at the lower end of the armature shaft is completely housed by the 15 driving wheel. The casing surrounding the armature and the field magnet is of simple construction and easy to manufacture.

It will be seen that by turning the link 27 about its bolt 30 and by turning the stud 21a about the pivot bolt 29, that the lamp may be moved toward and from the center of the bicycle wheel, which permits of positioning the lamp for any size wheel without shifting the brackets 31, 32. Furthermore, 20 by swinging the stud 21a about the pivot 29, I am able to bring the axis of the armature into a vertical line passing through the axis of the bicycle wheel, and thus bring the armature shaft into a plane intersecting 25 the center of said wheel, and so insure the free and easy running of the driving wheel 12 on the tire of the bicycle wheel. Two adjustments may, therefore, be readily made, one, a shifting of the lamp toward and from 30 the center of the wheel and the other a shifting of the axis of the armature so as to bring it into a plane intersecting the center 35 of the wheel.

It is obvious that minor changes in the 40 details of construction and arrangement of parts may be made without departing from the spirit of the invention, as set forth in the appended claims.

Having thus described my invention, what 45 I claim as new and desire to secure by Letters Patent, is:—

1. A generator lamp comprising a magnet, a vertically disposed armature rotating therein and having a shaft projecting at 50 both ends beyond said magnet, a casing inclosing the magnet and having top and bottom cap plates, each having an annular outwardly extending collar through which the shaft extends, ball bearings located in said 55 collars, a drive wheel on the lower end of the shaft provided at its upper end with a sleeve inclosing the lower collar, a reflector having a neck or sleeve on the lower side fitting the upper of said collars, a lamp 60 mounted on the upper end of the armature

shaft to turn therewith and extending into the reflector, and electrical connections for the lamp leading to the armature winding.

2. A generator lamp comprising a magnet, a vertically disposed armature rotating 70 therein and having a shaft projecting at both ends beyond the magnet, a casing inclosing the magnet and having top and bottom cap plates, each having a cup-like collar through which the shaft projects, ball 75 bearings located on the shaft within said cup-like collars, a drive wheel secured to the lower end of the shaft and formed with a sleeve inclosing the lower collar, a vertically disposed reflector having a neck on its lower 80 side inclosing the upper cup-like collar, a lamp mounted on the upper end of the shaft to turn therewith within the reflector, and electric connections for the lamp leading to the armature winding.

3. A generator lamp comprising a magnet, a casing therefor, an armature rotating in the magnet and provided with a shaft having an operating wheel, a lamp in electric connection with the armature winding, 90 a post or rod extending through the casing, a pivot stud for the casing, a spring on the stud engaging the casing to swing it inwardly and hold the drive wheel against the operating means, and a yielding detent 95 mounted on the stud and at its outer end adapted to engage said post or rod to hold the drive wheel away from its operating means.

4. The combination with a generator lamp 100 casing having upper and lower cap plates, of a bolt or rod holding said cap plates together, a pivot stud in rear of and parallel with said bolt or rod, a spring on the stud engaging the bolt or rod to swing the casing 105 in one direction, and a yielding detent mounted on the pivot stud and adapted to engage said bolt or stud and hold the casing against the action of said spring.

5. The combination with a generator lamp 110 having a vertical armature shaft provided at its lower end with a drive wheel for the purpose described, a pivot stud on which the lamp is mounted to swing laterally, a spring on the stud pressing the lamp laterally to bring the drive wheel into operative 115 relation with a bicycle tire, a link adjustably pivoted at its forward end to the lower end of said pivot stud by a transverse pivot, and a bracket for the bicycle fork, to which 120 bracket the rear end of the said link is adjustably pivoted by a transverse pivot, whereby two adjustments of the lamp are afforded as described.

6. A generator lamp for bicycles and the 125 like, including in combination, a generator, a lamp associated with the generator, said generator having a rotating part located in a plane substantially at right angles to the plane of a bicycle wheel, a driving wheel 130

carried by said rotating part, a supporting bracket for the lamp, yielding means for swinging said lamp in a direction toward the plane of the bicycle wheel for holding the said driving wheel in engagement therewith, and a yielding pin carried by the bracket and adapted to cooperate with a member carried by the lamp for positively holding said lamp out of engagement with the bicycle wheel.

7. A generator lamp for bicycles or the like including in combination, an armature, a V-shaped field magnet associated with said armature, a casing including a body portion and end plates inclosing said armature and

field magnets, said end plates having bearings for the armature shaft and the armature shaft projecting beyond said bearings, a driving wheel secured to the lower end of said armature shaft and having a projecting sleeve housing the adjacent bearing, a sleeve attached to the upper end of said armature shaft and having a socket for a lamp, a lamp fixed in said socket and rotating with said armature, and a reflector supported by the casing and surrounding the lamp.

In testimony whereof I hereunto affix my signature in the presence of two witnesses.

HARRY RANDOLPH VAN DEVENTER.
